[57] CLAIM

The ornamental design for a cycle pedal, as shown and
described.

DESCRIPTION

FIG. 1 is a top plan view of the cycle pedal showing my
new design, the bottom plan view being identical
thereto;

FIG. 2 is a front elevational view of the cycle pedal, the
rear view being identical thereto;

FIG. 3 is an elevational view of one side of the cycle
pedal, the other side being identical thereto; and

FIG. 4 is a sectional view taken along the line IV—IV
of FIG. 1, the remaining exposed surfaces being plain
and unornamented.
